PUNCH

Clarence E. Mange, St. Louis, Mo., assignor to
 Jackes-Evans Manufacturing Company, St.
 Louis, Mo., a corporation of Missouri

Application May 7, 1938, Serial No. 206,591

11 Claims. (Cl. 184—119)

This invention relates to punches, and with regard to certain more specific features to a sheet-metal punch.

Among the several objects of the invention may be noted the provision of a sheet metal punch which will punch a hole of the proper form in adjacent layers of sheet metal for the reception of so-called sheet-metal fastening screws; the provision of a punch of the class described which will avoid undesirable deformation of unbacked sheet metal during the punching operation; and the provision of a punch of the class described which may be operated at a high speed and with little effort. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawing, in which are illustrated several of various possible embodiments of the invention,

Fig. 1 is a vertical section of one form of the punch;

Fig. 2 is a view similar to Fig. 1 showing another form;

Fig. 3 is a bottom plan view of Fig. 1;

Fig. 4 is a fragmentary section showing another form of the invention, parts being shown in elevation;

Fig. 5 is a view similar to Fig. 4 showing another form;

Fig. 6 is a horizontal section taken on line 6—6 of Fig. 5;

Fig. 7 is a side elevation, on a reduced scale, illustrating a step carried out in the use of the form of the invention shown in Fig. 1; and,

Fig. 8 is a fragmentary view similar to Fig. 1 showing a punching operation just after completion.

Similar reference characters indicate corresponding parts throughout the several views of the drawing.

Much light sheet-metal work requires holding screws for holding adjacent sheets together. In order to make the necessary holes for these screws, it is preferable that they be punched so as to obtain a hole with a more or less ragged edge which tends to hold the metal screw much firmer than would a drilled hole. Heretofore, the disadvantage of punching holes has been that in many instances it was impossible to back a given area of sheet metal with any support

against the blow which was used for the punching operation. As a result, this method is not used. Drilling is slow, costly, and provides too smooth a hole for best holding of the screw. The present invention provides a punch which will properly make the necessary holes without the requirement of backing means.

Referring now more particularly to Fig. 1, there is shown at numeral 1 a tube which is threaded into a nipple 3. The large end of the nipple 3 carries an extension 5 which is inferiorly flanged for the purpose of holding the end 17 of a tension spring 15, as shown at 7. Around the lower end of the extension is a rubber or like friction ring 9. As the drawing shows, the lower end of the ring 9 extends below the lower end of the extension 5.

Along the center of the tube 1 is a stem 11. At the upper end of the stem is fastened a knob 13. Near this upper end is fastened the upper end of the tension spring 15. The stem 11 passes through the spring and at its lower end carries a removable shank 19. The shank 19 is threaded to the stem 11 and has a point 21 which preferably is of pyramidal form rather than conic. Any form of the point 1 which has angles is preferable to one which does not, for reasons which will appear, although a round form is operative.

Fig. 1 illustrates a first step in the operation of producing a hole in adjacent layers of sheet metal 23. The point 21 is set down exactly where desired. Then the tube 1 is pushed down until the friction ring 9 touches the sheet metal 23, or, if desired, the point 21 may be drawn back and the anti-skid device 9 may be initially applied to the sheet metal 23.

Then, the knob 13 is drawn back (Fig. 7) so that the point 21 is positioned as far back as possible in the tube 1. Then by releasing the knob 13, the assembly comprising knob 13, stem 11 and shank 19 attains a high velocity before piercing, as shown in Fig. 8. This is because of the relatively long stroke which permits of sufficient time to elapse when the knob 13 is released for the given acceleration of the spring 11 to bring about the required high velocity. It is desirable that the weight of this assembly be low. This is because a body moving at high velocity has a piercing or cutting action which increases rapidly with an increase of velocity. The kinetic energy of the assembly is proportional to its mass, multiplied by the square of its velocity. Therefore, comparatively less is to be gained in the matter of increasing kinetic energy 55

by increasing the mass; and more is to be gained by increasing the velocity, because the effect of this goes up as the square. Furthermore, increasing the mass has the following undesirable effect: When the point 21 presses the sheet metal 23, the assembly is decelerated. The force of deceleration is necessarily provided by the sheet iron 23. This force is proportional directly to the mass and directly to the deceleration of the system being decelerated. Therefore, since not much piercing effect is to be gained by increasing the mass of the system 11, 13, 18, and a disadvantageous force is applied to the sheet metal 23 in decelerating this system, it should be made as light as possible. The stroke of the device should be made as long as possible so that maximum increase may occur in the desirable velocity.

It will also be seen that, if the mass of the assembly 18, 11, 13 is increased, the maximum velocity obtainable from a given acceleration during a given time would be reduced if this mass were greater. Thus, every reduction in the mass of this assembly results in the decrease in undesirable effects and increase in desirable effects.

Marking punches heretofore have been made in which energy is stored in a spring. Upon pressing the punch to the surface marked, the final pressure released the spring to cause a member to strike the punch. This invention differs from these structures, because, in the case of these, the punch just after the time of initial contact with the metal to be marked (not pierced) is not even in motion. In the case of the present invention, the punch when it strikes the sheet metal is operating at high velocity.

In Fig. 2 is shown another form of the invention in which like numerals designate like parts. In this case, a compression spring 15' is used having a reaction against enclosing head 25 on the tube 1, and a pin 27 on the stem 11. The operation is analogous.

I have found that improvement in piercing action is effected if the point 21 has a rotary motion as it enters the sheet metal 23. Two ways of obtaining such rotary motion are shown in Figs. 4 and 5. In Fig. 4, the compression spring 15' is shown, with the rotary mechanism. This rotary mechanism is as follows:

At the bottom end of the shank 11, I provide a socket 28 in which is slidably arranged a shank 31. The shank is part of a member to which the punch shank 18 is screwed. Helical slots 33 in the stem 11 adjacent the shank 28 are adapted to receive the ends of a cross pin 35 in the shank 31. A spring 37 normally forces the shank 31 downwardly so that the pin rests at the lower ends of slots 33.

From the above, it will be seen that when the device of Fig. 4 is operated, the point 21 enters the sheet metal slightly, and then the camming action of the advancing shank 11 at the slot 33 tends to rotate the assembly of shank 31 with the punch 18. Therefore, during the punching operation, the punch has a rotary tendency which improves the piercing action.

In Fig. 5 is shown another method for obtaining a rotary action. In this case, the compression spring 15' is again used, and the ends of the pin follower 27 which carry its reaction to the shank 11 are also permitted to slide in grooves 39. The lower portions of the grooves are twisted as shown at 41. The twist is arranged at an elevation such that the resulting twisting action on

the punch 21 occurs at about the time that the punch enters the sheet metal.

In both forms of the invention shown in Figs. 4 and 5, the reaction to twisting is obtained by the friction device 8 on the sheet metal. This device 8 also serves to prevent sidewise slipping in all forms of the invention.

From the above it will be seen that the invention provides a punch in which a relatively light-weight piercing assembly is provided with a long stroke so that time enough elapses upon release that the accelerating spring may accelerate the punch to a high punching velocity. The fact that the punching assembly has low weight means that the force of deceleration is lower and that the sheet metal 23 will not be substantially deformed during punching. The sizes of the parts are arranged to accomplish these ends for given thicknesses of sheet metal.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawing shall be interpreted as illustrative and not in a limiting sense.

I claim:

1. A sheet metal punch comprising a portion adapted to be held against the sheet metal, a movable punch assembly having a point and adapted manually to be retracted from said sheet metal, and reacting means between said punch assembly and said body portion to accelerate the punch assembly toward the sheet metal to provide therefor a substantial velocity before and as it strikes the sheet metal.

2. A sheet metal punch comprising a portion adapted to be held against the sheet metal, frictional holding means at the point of contact, a movable punch assembly of relatively low mass having a point and adapted manually to be retracted from said sheet metal, and spring reacting means between said punch assembly and said body portion whereby when the punch is released it is accelerated to attain a substantial velocity before and as it strikes the sheet metal.

3. A sheet metal punch comprising a relatively long cylindrical portion, a relatively long shank in said cylinder, a punch at one end of said shank, spring means reacting between the shank and said cylinder whereby upon withdrawing the shank from the cylinder, said spring means accelerates the shank and punch assembly so that it attains a relatively high velocity before and as the punch strikes the sheet metal.

4. A sheet metal punch comprising a relatively long cylindrical portion, resilient friction means at one end of said cylinder, a relatively long shank in said cylinder, a punch at one end of said shank, spring means reacting between the shank and said cylinder whereby upon release after withdrawal of the shank from the cylinder, said spring means accelerates the shank and punch assembly to attain a relatively high velocity before and as the punch strikes the sheet metal.

5. A punch comprising a part adapted to be held stationary to sheet metal, a part retractable therefrom, a punch on said last-named part, spring means between the retractable part and the stationary part adapted to have energy stored therein upon substantial retraction of the punch from the sheet metal, and adapted to accelerate

the punch when released, said punch when it strikes the sheet metal having a velocity high enough to pierce a hole through the sheet metal.

6. A punch comprising a tube, a sleeve at one end of said tube providing friction means between the tube and sheet metal to be punched, a slideable shank in the tube, a punch on the end of the shank adjacent said friction device, means at the opposite ends of the shank for manually grasping and retracting the shank with the punch, spring means reacting between said shank and said tube and adapted upon release after withdrawal of the shank to accelerate the shank and the punch to a high degree as the punch reaches the sheet metal.

7. A punch comprising a tube, a sleeve at one end of said tube providing friction means between the tube and the sheet metal to be punched, a slideable shank in the tube, a punch on the end of the shank adjacent said friction device, means at the opposite ends of the shank for manually retracting the shank with the punch, spring means reacting between said shank and said tube and adapted upon release after withdrawal of the shank to accelerate the shank and the punch to a high degree as the punch reaches the sheet metal, and means for rotating the punch as it strikes said sheet metal.

8. A sheet metal punch comprising a body portion adapted to be held against the sheet metal, a movable punch assembly having a point adapted manually to be retracted from said sheet metal, spring reacting means between said punch assembly and said body portion whereby when the punch is released it is accelerated to attain a substantial velocity as it strikes the sheet metal, and means for causing rotation of the punch as the sheet metal is pierced.

9. A sheet metal punch comprising a relatively long cylinder, anti-skid means in one end of the cylinder adapted to contact sheet metal, a shank in said cylinder, a punch on the shank adjacent said anti-skid device, means at the other end of

the shank and external to the cylinder adapted to form means for withdrawing the shank and punch from the cylinder, and an elongated tension spring, one end of said spring being fastened to said cylinder near the anti-skid device, and the other end being fastened to said shank near said manual withdrawing means.

10. A sheet metal punch comprising a body portion adapted to be held against the sheet metal, a movable punch assembly having a point adapted manually to be retracted from said sheet metal, reacting means between said punch assembly and said body portion whereby when the punch is released it is accelerated to attain a substantial velocity as it strikes the sheet metal to pierce it, means for causing rotation of the punch as the sheet metal is pierced, said last-named means comprising a groove in the portion which is held against the sheet metal, said groove having an elongated part parallel to the axis of the body portion and a twisted part, and a follower movable in said groove and adapted to accelerate along said elongated part of the groove and to twist the punch assembly after substantial acceleration and as it strikes.

11. A sheet metal punch comprising a body portion adapted to be held against the sheet metal, a movable element adapted to be retracted from said sheet metal, biasing means between said movable element and said body portion whereby when the movable element is released it is accelerated to attain a substantial velocity, a punch head slideable on said movable element and adapted to strike the sheet metal at said substantial velocity to pierce it, and means for causing relative rotation of the punch head with respect to the movable element as the sheet metal is pierced comprising means normally biasing the punch head forward in the direction of movement, and cooperating means between the punch head and the movable element to effect twisting during relative motion upon impact with the sheet metal.

CLARENCE E. MANGE.
